United States Patent Office

Des. 220,559
Patented Apr. 20, 1971

220,559

SIGN

James T. Hight, Darien, Conn., assignor to American
Dairy Queen Corporation, Minneapolis, Minn.

Filed Mar. 21, 1969, Ser. No. 16,360

Term of patent 14 years

Int. Cl. D20—03

U.S. Cl. D96—12

FIG. 1 is a perspective view of a sign embodying my new design;

FIG. 2 is a front elevational view thereof, the rear being the same as the front shown;

FIG. 3 is a side elevational view thereof; and

FIG. 4 is a top plan view thereof.

The characteristic feature of my design resides in the trapezoid shaped sign panel as shown.

I claim:

The ornamental design for a sign, as shown and described.
